TOOLHOLDER

Victor E. Griffin, Cicero, Ill., assignor to Atlas
Press Company, Kalamazoo, Mich.

Application July 12, 1944, Serial No. 544,590

2 Claims. (Cl. 29—96)

The present invention relates to new and useful improvements in tool holders for lathes, shapers, and other machine tools and has for its primary object to provide, in a manner as hereinafter set forth, a device of this character which is capable of substantially universal adjustment whereby right hand, left hand or straight turning or cutting at any angle may be done without the necessity of changing holders or for removing the holder from the tool post.

Another very important object of the invention is to provide an adjustable tool holder of the aforementioned character comprising a unique construction and arrangement for firmly clamping the tool and for positively securing same in adjusted position.

Other objects of the invention are to provide a tool holder of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in side elevation of a tool holder constructed in accordance with the present invention, showing a bit mounted therein;

Figure 2 is a top plan view thereof;

Figure 3 is a view principally in vertical section, taken substantially on the line 3—3 of Figure 2;

Figure 4 is a view in transverse section, taken substantially on the line 4—4 of Figure 1;

Figure 5 is a side elevational view showing the holder with an inside threading tool mounted therein.

Referring now to the drawing in detail, it will be seen that reference character 1 designates a shank to be secured in the usual tool post of a lathe or other machine tool. Extending into the shank 1 from the forward end thereof is a rearwardly inclined kerf 2. Formed inwardly with the forward end of the shank 1 and projecting forwardly therefrom is a pair of spaced, vertically aligned upper and lower eyes 3 and 4, respectively. The eye 4 is provided with a serrated lower end 5.

Mounted for rotary adjustment in the eyes 3 and 4 is a post 6 having a threaded upper end portion. The post 6 is provided, on its lower end,

with a head 7 having a serrated surface 8 which is engageable with the surface 5 of the eye 4. Extending downwardly into the post 6 from the upper end thereof is a slot 9 the lower end wall 10 or bottom 10 of which is inclined in the plane of the lower wall of the kerf 2.

Encircling the post 6 between the eyes 3 and 4 is a sleeve 11 having at diametrically opposite sides thereof openings 12 which communicate with the slot 9 immediately adjacent the bottom wall 10 thereof. Forming integrally with the sleeve 11 in the upper portion thereof and extending between the openings 12 is a substantially wedge-shaped bar 13 the lower surface of which parallels the lower end wall 10 of the slot 9. A cap nut 14 is threaded on the upper end portion of the post 6 and engaged with the eye 3 for clamping the assembly on a bit 15 or other tool.

20 In use, the sleeve 11 is positioned between the eyes 3 and 4 and the post 6 is inserted upwardly through said eyes, the slotted portion of said post straddling the bar 13. The cap nut 14 is then threaded on the upper end portion of the post 6 and the bit 15 is inserted in the openings 12 and slot 9. The cap nut 14 is then tightened for firmly clamping the bit 15 between the lower end 10 of the slot 9 and the complementary lower face of the bar 13. By simply loosening the cap nut 14, the members 11 and 6 with the bit 15 therein may be rotatably adjusted to any desired position. The kerf 2 accommodates the stock of the bit 15 when straight cutting is to be done or when rotatably adjusted said bit.

25 The members 6 and 11 may be removed and replaced with posts and sleeves which will accommodate therein other tools. For example, in Figure 5 of the drawing there is shown a sleeve 15 which is formed to accommodate an inside threading tool 16. The post 17 is also formed to accommodate the tool 16. In this construction, the tool 16 may be rotatably adjusted in the members 15 and 17.

30 It is believed that the many advantages of an adjustable tool holder constructed in accordance with the present invention will be readily understood and although preferred embodiments are as illustrated and described, it is to be understood that further modifications and changes in the details of construction may be resorted to which will fall within the scope of the invention as claimed.

35 What is claimed is:

1. A tool holder comprising a shank, a pair of spaced, aligned eyes on one end of said shank,

a post mounted for rotary adjustment in the eyes and having a slot extending thereinto from one end thereof for the reception of a tool, a sleeve encircling the post between the eyes and having openings therein accommodating the tool, a bar in the sleeve traversing the slot and co-operable with one of the walls thereof for clamping the tool in position, a cap nut threaded on one end portion of the post and engageable with one of the eyes for clamping said bar and said post on the tool, and coacting means on the post and the other eye for securing said post in adjusted position.

2. A tool holder of the character described comprising a shank, a pair of spaced, aligned eyes on one end of the shank, said shank having a kerf extending thereinto from said one end thereof between the eyes, a vertical post mount-

ed for rotary adjustment in the eyes, said post having a slot extending downwardly thereinto from the upper end thereof for the reception of a tool, the lower end wall of the slot being inclined, a sleeve encircling the post between the eyes, and having openings therein accommodating the tool, a bar traversing the upper portion of the sleeve and including a lower surface paralleling the lower end wall of the slot in the sleeve, a cap nut threaded on the upper end portion of the post and engaged with one of the eyes for clamping the bar and said post on the tool, and a head on the lower end of the post engaged beneath the other eye, said other eye and said head comprising coacting serrated surfaces for positively securing the post in adjusted position.
